Charles E. Foster

UNITED STATES PATENT OFFICE.

JEFFERSON WILSON, OF BEAVER FALLS, PENNSYLVANIA.

CHURN-POWER.

SPECIFICATION forming part of Letters Patent No. 257,797, dated May 9, 1882.

Application filed December 31, 1881. (No model.)

To all whom it may concern:

Be it known that I, JEFFERSON WILSON, a citizen of the United States, and a resident of Beaver Falls, Beaver county, Pennsylvania, have invented certain Improvements in Churn-Powers, of which the following is a specification.

My invention is an animal-power, fully described hereinafter, which is of simple construction, capable of ready adjustment, and easily operated, and the movable parts of which may be brought very nearly within the dimensions of the supporting-frame.

In the drawings, Figure 1 is a side elevation of the apparatus, showing the same arranged for operation; Fig. 2, the same, showing the apparatus arranged for stowage or transportation. Fig. 3 is an end view, looking in the direction of the arrow, Fig. 2, the web being removed. Fig. 4 is an enlarged longitudinal section through the web and links. Fig. 5 is a plan of one of the links. Fig. 6 is an enlarged sectional view of the dash-rod and clamp.

The frame W of the apparatus consists of suitable posts and cross-bars.

The web-supporting frame A carries the wheels C C', and is pivoted or hung on a cross-bar, f, between bars B B of the frame W. The endless web I passes around the wheels C C'.

To a post, E', of the frame is pivoted a lever, H, to one end of which is attached a rod, O, connected at the opposite end to a balance-wheel, J, secured to the shafts of the wheels C C, and to the other end of said lever H is pivoted a clamp, P, for making detachable and adjustable connection with the dash-rod of the churn, as hereinafter more fully set forth.

In the side pieces of the web-frame A, near the outer ends, are longitudinal slots e, in which slides a cross-bar, g, and the projecting ends of the latter bear in notches u in the posts E' E' of the frame W, or in plates attached thereto, for the purpose of supporting the web-frame at different inclined positions to which it may be adjusted, Fig. 1.

The wheels C C have peripheral lugs c c, which fit between the slats Y composing the web and insure the revolution of the wheels with the web. Flanges s on the sides of the wheels prevent the web from being displaced. Each web-link consists of one piece of metal

comprising a stem, a, with a head, b, at one end and enlarged at the other to form a loop, c', and has sockets e e, adapted to receive the head of the next loop, which will be retained therein, as shown in Fig. 4, thus pivoting the links, with their slats Y, together. By applying the slats Y to the links and securing them by screws passed through perforated lugs s of the links the cross-heads are retained in their sockets without interfering with their swinging motion, thus permitting the web to bend in passing round the wheels.

The clamp P has a longitudinal recess with two or more spurs, n, and a cam-lever, Q, is hung opposite said recess, and when turned to the position shown forces the churn dash rod against the spurs, and they hold it firmly.

As the animal faces the end of the apparatus where the churn is located, it sometimes occurs that froth and matter from the mouth fall in the vicinity of the churn. I obviate this by employing a head-board, R, hinged to the end of the frame, so that it can be turned down below the head of the animal. A double-hooked catch, x, constructed as shown, is so pivoted that the head-board may be secured in either position shown in Figs. 1 and 2.

The bar or pivot f of the web-frame may be movably connected to the supporting-frame to admit of the longitudinal adjustment of said web-frame. Thus the bars may rest in bearings v, movable on the bars E E'.

Connection having been made between the dash-rod of the churn and the lever H by means of the clamp P, and between the fly-wheel J and lever H by means of the rod O, and the frame A being adjusted at the proper angle, the animal is placed upon the web, and by putting the same in motion causes the drums C C' to revolve, thus actuating the lever H and the churn-shaft.

When the machine is not in operation the bar g of the frame A may be removed from its bearings in the posts E, and the frame, its web, and drums, with the lever H, may be turned to the positions shown in Fig. 2, and there maintained by merely sliding the bar g along the slot e until it has reached a position where it can rest in notches y of the bars M of the supporting-frame.

As the frame A is pivoted between its ends,

one end will be carried inward as the other is turned up, so as to bring the entire frame and its drums nearly within the limits of the supporting-frame, thereby reducing the apparatus 5 to a compact form for stowage.

If desired, the apparatus may be mounted upon rollers or other devices to facilitate its movement from place to place.

It will be apparent that other means than 10 those described may be used for securing the frame at any desired angle.

I may drive a rotary churn by a belt passing round the fly-wheel and round a pulley on the churn-shaft, or otherwise.

15 I claim—

1. The combination, in an animal-power, of the supporting-frame W, the web-frame A, pivoted within said frame W, between its ends, so that it may be turned within the frame to a 20 vertical position, and provided with a device, substantially as described, for securing it in any position to which it may be adjusted, substantially as set forth.

2. The combination, in an animal-power, of 25 the supporting-frame W, its notches y and u, and the pivoted web-frame A, provided with the sliding bar g, substantially as set forth.

3. The web-link provided with a cross-head at one end and with sockets at the opposite end, adapted to the cross-head of the adjacent link, all cast in one piece, substantially as set forth.

4. The combination of the links, their cross-heads and sockets, each cast in one piece, as set forth, and slats Y, retaining the cross-heads 35 in the sockets, substantially as described.

5. The combination, with the operating-lever H, of the pivoted clamp provided with a cam-lever, Q, grooved and spurred, substantially as described, for the purpose set forth. 40

6. The combination, with the supporting-frame of the apparatus, of a hinged head-board, R, and devices for securing said head-board in its different positions, substantially as described.

45 In testimony whereof I have signed my name to this specification in the presence of two subscribing witnesses.

JEFFERSON WILSON.
